(57) **CLAIM**

The ornamental design for the pole saw, as shown and described.

DESCRIPTION

FIG. 1 is a top perspective view of a pole saw in accordance with the present invention;

FIG. 2 is a right side view of the pole saw of FIG. 1;

FIG. 3 is a left side view of the pole saw of FIG. 1;

FIG. 4 is a bottom view of the pole saw of FIG. 1;

FIG. 5 is a top view of the pole saw of FIG. 1;

FIG. 6 is a front view of the pole saw of FIG. 1; and,

FIG. 7 is a back view of the pole saw of FIG. 1.

The broken lines in the drawings illustrate portions of the pole saw and form no part of the claimed design.
